SKI CLIP

John W. Kelley, Stratton, Maine

Application June 20, 1938, Serial No. 214,831

3 Claims. (Cl. 280—11.35)

This invention appertains to new and useful improvements in clips for skis and more particularly to a simple and efficient form of clip or clamp for securing the shoe properly to the ski.

5 The principal object of the present invention is to provide a clip of the clamp type which will conveniently and effectively grip the shoe in a manner firmly holding the same against separation of the shoe from the ski.

10 These and various other important objects and advantages of the invention will become apparent to the reader of the following specification.

In the drawings—

15 Figure 1 represents a fragmentary top plan view of the ski and clip.

Figure 2 is a side elevational view.

Figure 3 is a fragmentary bottom plan view of the clip.

20 Figure 4 is a sectional view on the line 4—4 of Figure 3.

Figure 5 is a fragmentary side elevational view of the actuating lever.

25 Referring to the drawings wherein like numerals designate like parts, it can be seen that numeral 5 represents the usual ski, while numeral 6 denotes the foot plate which is supported above the ski 5 by spacer tubes 7 through which and the plate 6 screws 8 are disposed and driven as shown in Figure 2 into the ski 5.

30 The clamp means consists of a slide bar 9 having a slot 10 in one end portion thereof in which the bolt 11 can be adjusted to give the proper throw to the front clamp members. The clamp members are denoted by numerals 12—12 and 13—13. The

35 clamp members each consists of the vertical portion *a* having the inturned lug portion *b* at its upper end and the horizontally disposed and arcuately-shaped shank 14 extend from these clamps, with the shanks of the clamps 12 apertured at their forward ends with the bolt 11 disposed through these apertures. The arcuate-shaped shanks 14 of the clamps 13—13 are pivotally secured to the slide bar 9 by the bolt 15. The intermediate portions of the shanks 14 are offset

40 as at 16 so as to accommodate the slide bar 9, the slide bar being formed with an eye 17 at its forward end to receive the laterally disposed hook portion 18 of the rod section 19.

45 On the ski 5 at a point forwardly of the plate 6 is attached the angle member 20 to the upstanding portion of which the lever 21 is pivotally secured as at 22. The rod section 23 having the laterally disposed end portion 24 is disposed

50 through one of the openings 25 and has a nut 26

on the threaded portion thereof to prevent displacement thereof from the lever 21.

A turnbuckle 27 is provided between the remaining ends of the rod sections 19—23.

5 Thus it can be seen that when the lever 21 is swung rearwardly, the slide bar 9 will be moved rearwardly under the plate 6 so that the shanks 14 of the clamps will be moved laterally through their corresponding guides 28 so as to release the clip to permit detachment of a shoe.

10 Screws 29 are driven into the bottom side of the plate 6 in a manner to form a guideway for the slide bar 9, the longitudinal edge portions of the slide bar 9 being beveled for engagement with the members 29.

15 While the foregoing specification sets forth the invention in specific terms, it is to be understood that numerous changes in the shape, size and materials may be resorted to without departing from the spirit and scope of the invention as 20 claimed hereinafter.

Having described the invention, what is claimed as new is:

1. In a ski structure, a clip, said clip comprising a foot plate, a plurality of clamp members on the 25 foot plate arranged in pairs, a slide bar disposed under the plate and being operatively connected with the clamp members for simultaneous operation thereof and means for independently adjusting the throw of one pair of clamping members 30 relative to the remaining clamping members.

2. In a ski structure, a clip, said clip comprising a foot plate, a plurality of clamp members on the 35 foot plate arranged in pairs, a slide bar disposed under the plate and pivotally connected to one end of each of the clamp members, means for adjusting one pair of clamp members longitudinally of the slide to vary the throw of the clamp members relative to the other clamp members and a swingable lever for operating the said slide bar.

3. In a ski structure, a clip, said clip comprising a foot plate, a plurality of clamp members on the 45 foot plate arranged in pairs, a slide bar disposed under the plate and being operatively connected with the clamp members, each of the said clamp members being provided with an arcuate-shaped shank pivotally connected to the slide bar, said slide bar having a longitudinal slot therein, a bolt carried at the pivoted end of one pair of clamp 50 members adjustable in the slot to vary the throw of said clamp members relative to the remaining members and guide means on the under side of the plate for the said shank.

JOHN W. KELLEY. 55
